INVENTOR
Frederick R. Bishop
By *Corrado E. Bellone*
ATTORNEY

UNITED STATES PATENT OFFICE.

FREDERICK R. BISHOP, OF NORTH ATTLEBORO, MASSACHUSETTS, ASSIGNOR TO THE BISHOP COMPANY, A CORPORATION OF MASSACHUSETTS.

OPHTHALMIC MOUNTING.

1,393,340.

Specification of Letters Patent. Patented Oct. 11, 1921.

Application filed April 6, 1921. Serial No. 459,190.

To all whom it may concern:

Be it known that I, FREDERICK R. BISHOP, a citizen of the United States, residing at North Attleboro, in the county of Bristol and State of Massachusetts, have invented 5 certain new and useful Improvements in Ophthalmic Mountings, of which the following is a specification.

My invention relates to lens frames, comprising rims of the non-metallic type.

In structures of this type the difference in character of the materials of the constituent parts make it difficult to firmly connect or unite the attached or adjacent parts.

15 The essential objects of my invention are to afford a secure and rigid fastening of the bridge or spring to the lens rims; to render the fastening invisible to the observer from the front; and to attain these ends in a simple and inexpensively constructed means; 20 and adapted to facile assemblage.

To the above ends essentially my invention consists in such parts and in such combinations of parts as fall within the scope 25 of the appended claims.

In the accompanying drawings which form a part of this specification,

Figure 1 is a front elevation of a pair of spectacles or eyeglasses embodying my invention,

Fig. 2, an enlarged section of the frame on line 2—2 of Fig. 1,

Fig. 3, an enlarged longitudinal section of a portion of the same on line 3—3 of 35 Fig. 2,

Fig. 4, a section of the frame taken on line 4—4 of Fig. 1,

Fig. 5, a longitudinal section of a portion 40 of a detached rim taken on line 3—3 of Fig. 2, and

Fig. 6, a perspective view of one of the attaching members before insertion into a rim.

Like reference characters indicate like 45 parts throughout the views.

In the present and preferred construction illustrated 10 is the bridge or spring, 11 the rims or eyes of xylonite or other non-metallic material, 12 the end pieces, and 13 50 the lenses.

Each rim is provided with the usual in-

ternal annular groove 15, preferably V shaped in cross section. A longitudinally disposed oblong slot 16 is located in each rim extending diametrically therethrough. 55 The walls 17 at the ends of the slot or opening are in this case inclined.

Fast to each end of the bridge 10 or integral therewith, and at an angle thereto, 60 is a broad flat arcuate or segmental attaching plate 19 having preferably inclined end faces 20. The curved edge of each plate remote from the bridge is provided with a longitudinal slit or groove 21 extending the 65 entire length of the plate forming parallel bifurcated portions or lips 22, as shown in Fig. 6.

To apply a rim to one end of the bridge the attaching plate 19 is inserted as a sliding fit into the opening 16 of the rim, and 70 then by means of an angular swaging tool inserted between the lips the latter are forced apart outwardly and downwardly upon the walls of the groove or channel 15 and conform to their angular inclinations. 75 The lens 13 is thereafter inserted in the annular groove 15 in the usual manner.

I claim:

1. In an ophthalmic mounting, a rim provided with an oblong opening, a bridge, an 80 attaching plate on the bridge seated in the opening, and diverging lips on the plate engaging the rim.

2. In an ophthalmic mounting, a non-metallic rim provided with a longitudinally disposed opening, a bridge, a metallic attaching plate upon the bridge disposed at an angle thereto, and lips integral with the plate remote from the bridge overlapping 85 the rim.

3. In an ophthalmic mounting, a non-metallic rim provided with an oblong central opening formed with inclined ends, a bridge, a segmental attaching plate seated in the opening and registering with said 95 ends, and diverging lips on the edge of the plate opposite the bridge overlapping the rim.

In testimony whereof I have affixed my signature.

FREDERICK R. BISHOP.
